Attorney.

UNITED STATES PATENT OFFICE.

WILLIAM GIBSON, OF PITTSBURGH, PENNSYLVANIA.

BRAKE-SHOE.

1,349,129.

Specification of Letters Patent. Patented Aug. 10, 1920.

Application filed August 18, 1919. Serial No. 318,179.

To all whom it may concern:

Be it known that I, WILLIAM GIBSON, a citizen of the United States, and a resident of Pittsburgh, in the county of Allegheny and State of Pennsylvania, have invented a new and useful Improvement in Brake-Shoes; and I do hereby declare the following to be a full, clear, and exact description thereof.

10 My invention relates to brake-shoes, and has special reference to the class of brake-shoes which are provided with an inclosed metallic casing around a filling or body of frictional material for engagement with a 15 wheel in braking.

The object of my invention is to provide a cheap, simple and efficient form of a brake-shoe, wherein the ends or sides of such shoe will not cut into or wear down the 20 wheel on which it is used, and one in which such ends or sides will wear down evenly and uniformly with the filling of frictional material.

A still further object of the invention is 25 to keep the metal of the cap of the shoe from engaging the wheel when in use, so that when the shoe is worn down to such metal very little is left of the shoe and it then can be scrapped.

30 To these ends my invention consists, generally stated, in the novel arrangement, construction and combination of parts, as hereinafter more specifically set forth and described and particularly pointed out in the 35 claims.

To enable others skilled in the art to which my invention appertains to construct and use my improved brake-shoe, I will describe the same more fully, referring to the 40 accompanying drawings, in which:

Figure 1 is a plan or back view of a brake-shoe embodying my invention;

Fig. 2 is a side elevation, partly in section, of the same;

45 Fig. 3 is a longitudinal section of the shoe on the line 3—3 Fig. 1;

Fig. 4 is a bottom plan view of the shoe;

Fig. 5 is a like view showing another form of the invention;

50 Fig. 6 is a cross-section of the shoe on the line VI—VI Fig. 2; and

Fig. 7 is an end view of the form of shoe shown in Fig. 4.

Like symbols of reference herein indicate

like parts in each of the figures of the sheet 55 of drawings.

As illustrated in the figures of the drawings, my improved brake-shoe is shown at *a* and has the usual shape or curvature, such shoe being provided with an inclosing cap or 60 supporting member 1 and a frictional filling or body member 2 of frictional material inserted in said cap in any suitable manner. This filling member 2 is adapted to engage with the wheel and the rubbing or 65 frictional action of the brake-shoe upon the wheel is exerted by such frictional member, which consists of any suitable material, such as cast iron or composition of matter or other material secured within the cap 1 to 70 exert proper and sufficient friction upon the periphery of the wheel without the imposition of undue or excessive wear thereon and the loss of wheel metal consequent thereto, and such compositions are of a character 75 familiar to those skilled in the art.

The cap 1 is formed from any suitable material, preferably from band, sheet, plate or other metal having a substantial degree of strength and durability, such as malleable, 80 wrought or other steel or iron, and when formed from sheet or plate metal it is pressed or bent by suitable dies into a structure having an integral back wall 3, side lips 4 and end lips 5, as well as being open 85 at the front for the insertion of the filling member 2 and curved substantially in accordance with the periphery of the car wheel on which the brake-shoe is to be used. The side lips 4 and end lips 5 provide the 90 deep corners 4' on the casing 1 between such end and side lips to assist in supporting the filling member 2 and the plates hereinafter described.

The usual supporting lug 6 is connected 95 or fixed to the back 3 of the cap 1 in any suitable manner for connecting the shoe *a* to the Master Car Builders' standard brake-head or hanger (not shown) and is preferably separate therefrom, as shown, by having the inner ends 8 passed through slots 8' in said back and turned against the inner face of the same to connect said lug to said casing. Short bearing surfaces 7 are formed adjoining the ends on the back 3 100 of the cap 1 which are adapted to bear against bearings on the ends of the brake-shoe or hanger, and such bearings are pref-

erably recessed, as at 7'. Central or intermediate bearings on the head or hanger are adapted to abut against said back wall 3 of the cap 1 and on each side of the lug 6.

- 5 In the formation of the brake-shoe *a*, after the metallic cap 1 is formed, with the lug 6 connected to the back 3 in any suitable manner or as described, then the plates 9 are inserted within the cap and then the material composing the filling member 2 is inserted in such cap. These plates 9 as shown in Figs. 1, 2, 3, 4, 6 and 7 are formed of two L-shaped pieces and when placed within the cap 1 and against the filling member 2 will form the end and side walls of the finished shoe *a* by the short portions 9' thereon abutting the long portions 9" thereon and thus assist with such cap in holding the material comprising such member in place.
- 10 The plates 9 are made of any convenient relatively softer material, what is commonly known as vulcanized fiber having been found satisfactory in practical use, and they can be formed of different thicknesses, 15 and if desired, of the same thickness as the side lips 4 on the cap 1, so that their exterior surfaces are flush with the exterior surfaces of said lips, thereby strictly conforming in shape and size to the Master 20 Car Builders' standards. In order to hold such plates 9 against the lips 4 and 5 and allow such flush surfaces to be obtained, the plates are provided with a turned or bent portion 10 at their inner or upper edges 25 which forms seats 11 for the reception of the lower or outer end edges of said lips.

If desired, the plates 9 can be formed of U-shaped pieces, as shown in Fig. 5, in which case the short ends 9^a on the same can abut 30 against each other when in place in the shoe, while various other modifications and changes in the design and construction of my improved brake-shoe may be resorted to, without departing from the spirit of the 35 invention or sacrificing any of its advantages.

In the use of the term "soft" in the above specification and in the claims it will be understood that the material used for the 40 pieces composing the integral side and end walls of the brake-shoe, will be flexible and resilient, and is of such a nature as to be worn away itself by friction rather than cause the wearing away of the wheel to 45 which the brake-shoe is applied, while such term also includes such material which will not melt from the heat of such wheel on high-speed passenger trains, and thereby form a tempered or hard material as will 50 tend to cut into and injure such wheel. It has been found that the same raw stock as the regular vulcanized fiber when properly treated and pressed or formed to shape will 55 answer the purposes desired.

60 65 It will thus be seen that my improved

brake-shoe will prevent any possibility of the injury to or uneven wearing of the wheel throat and tread and will also enable the filling, ends and sides of the shoe to wear down evenly, uniformly and together, while such form of shoe will also avoid any excessive wear on the wheel by the ends and sides of the shoe and enable a strong and durable inclosure to be formed for the filling material.

70 It will also be seen that in the use of my improved brake-shoe, the metal of the cap will be kept from engaging with the wheel, so that the shoe can be used until it is worn down to such metal, thereby enabling only a small portion of such shoe to remain after being used to the limit, so that it can be scrapped without great loss in the material composing the shoe, while the ends and sides of the filling member will also 80 be protected by the side and end portions on the plates and such plates will assist the cap in holding the filling member in place. The form of such cap will also eliminate 85 waste and scrap in its manufacture.

90 What I claim as my invention and desire to secure by Letters Patent is:

1. A brake-shoe composed of integral plates each of which comprises more than one wall, a separate back supporting member, and a filling member within said back supporting member and plates.

2. A brake-shoe composed of integral plates, each of which comprises more than one wall, at least one of said walls being 100 formed of a soft material, a separate back supporting member, and a filling member within said back member and plates.

3. A brake-shoe composed of integral plates formed of a soft material and each 105 of which plates comprises more than one wall, a separate back supporting member, and a filling member within said back member and plates.

4. A brake-shoe composed of integral 110 plates formed of vulcanized fiber and each of which plates comprises more than one wall, a separate back supporting member, and a filling member within said back member and plates.

115 5. A brake-shoe composed of integral plates each of which comprises more than one wall, a separate back supporting member having side and end lips for supporting said plates, and a filling member within 120 said back member and plates.

6. A brake-shoe composed of integral plates formed of soft material and each of which plates comprises more than one wall, a separate back supporting member having 125 side and end lips for supporting said plates, and a filling member within said back member and plates.

7. A brake-shoe composed of integral plates formed of vulcanized fiber and each of 130

which plates comprises more than one wall, a separate back supporting member having side and end lips for supporting said plates, and a filling member within said back member 5 and plates.

8. A brake-shoe composed of integral plates each of which comprises more than one wall, a separate back supporting member having side and end lips, and a filling member within 10 said back member and plates, said side lips and the corresponding walls of the plates having their exterior surfaces flush with each other.

9. A brake-shoe composed of integral plates formed of soft material and each of which plates comprises more than one wall, a separate back supporting member having side and end lips, and a filling member within 15 said back members and plates, said side 20 lips and the corresponding walls of the plates having their exterior surfaces flush with each other.

10. A brake-shoe composed of integral plates formed of vulcanized fiber and each 25 of which plates comprises more than one wall, a separate back supporting member, having side and end lips, and a filling material within 30 said back member and plates, said side lips and the corresponding walls of the plates having their exterior surfaces flush with each other.

11. A brake-shoe composed of integral plates each of which comprises more than one wall, a supporting member and a sep-

arate back supporting member having end 35 and side lips, and a filling material within said back member and plates, each of said plates having a seat formed therein for the end of one of the side lips and a wall of each plate and the corresponding lip having 40 their exterior surfaces flush with each other.

12. A brake-shoe composed of integral plates formed of a soft material and each of which plates comprises more than one wall, a supporting member and a separate back 45 supporting member having end and side lips, and a filling material within said back member and plates, each of said plates having a seat formed therein for the end of one of the side lips and a wall of each plate 50 and the corresponding lip having their exterior surfaces flush with each other.

13. A brake-shoe composed of integral plates formed of vulcanized fiber and each of which plates comprises more than one 55 wall, a supporting member and a separate back supporting member having end and side lips, and a filling material within said back member and plates, each of said plates having a seat formed therein for the end 60 of one of the side lips and a wall of each plate and the corresponding lip having their exterior surfaces flush with each other.

In testimony whereof I, the said WILLIAM GIBSON, have hereunto set my hand.

WILLIAM GIBSON.
